UNITED STATES PATENT OFFICE.

FRANK W. PROVOST AND GEORGE B. HAYWOOD, OF HOUSTON, TEXAS.

LINT CONDENSER.

Application filed May 11, 1925. Serial No. 29,432.

Our invention relates to condensers for receiving cotton lint from delinting machines and forming it into a thin layer or bat so that it may be used.

It has been customary in delinting devices to receive the lint from the machines upon a single cylinder without making any provision for the discharge of the air passing through the device. The result has been an inefficient device requiring services of one or more attendants. Another objection is the escape of the dust and dirt into the air so that the operators are compelled to work in an atmosphere of dust and lint.

It is an object of our invention to provide a condenser in which the lint is received directly from the delinting machines to the condenser, and the air passing through the condenser device is discharged out of the building. It is also an object to provide an efficient screening area in the condenser so that all of the lint may be recovered in passing through the condenser and thus saved. It is also desired that a maximum screening surface be provided.

It is another object to provide an effective means for removing the lint from the screening cylinders in a smooth compact layer so that it may be most efficiently handled thereafter.

The invention also consists in certain details of construction and arrangement of the parts which will be set forth in detail in the specification which follows.

Referring to the drawing herewith, Fig. 1 is a central vertical section through the condenser embodying the invention. Fig. 2 is a vertical section on the line 2—2 of Fig. 1. Fig. 3 is a side elevation of the device. Fig. 4 is a similar elevation from the opposite side of the machine showing the suction chamber removed, and Fig. 5 is a rear elevation showing the connection thereof with the suction device. Like numerals of reference are employed to designate like parts in all the views.

The device consists of a housing 1, preferably made of sheet iron and shaped to efficiently house two parallel screening cylinders 2 and 3. The housing is provided on the forward side with a tubular opening 4, by means of which it may be connected to a flue, or pipe, leading to the various delinting machines from which the lint is received. This lint is drawn from the delinting devices to the condenser by means of a suction fan,

shown at 5 in Fig. 5. The suction fan is connected by means of a flue 6 and branching pipes 7 to the opposite ends of the two cylinders. There is, hence, a draught of air carrying the lint from the delinting machines through the opening 4 upon the cylinders, the air passing out through the ends of the cylinders at the side of the housing to the suction device 5, and is then discharged through the pipe 8 to the outside of the building.

The cylinders 2 are mounted upon transverse shafts 9 and 10, supporting the upper and lower cylinders respectively. The said shafts are mounted in supporting brackets 11 at one end and these shafts are squared at their ends to fit within said brackets and are thus held against rotation in said supports. The cylinders are mounted upon bearing sleeves 12 at their ends; the said sleeves are adapted to rotate upon their respective shafts and are secured at their inner ends 14 to the ends of the cylinders. Each sleeve 13 projects beyond the support 15 and has fixed thereon a pulley 16 by means of which the sleeve may be rotated on the shaft, thus rotating the cylinder.

The construction of the two cylinders and their mounting is practically identical. Each cylinder comprises a frame made up of a spider 17 at each end, consisting of a central hub and radial spokes connecting the same with a rim 18, said rim has an outwardly extending flange 19 thereon. The rims are connected by longitudinal bars, or rods, 20, which may be supported midway between their ends by a hoop, or band, 21. The outer surface of the cylinder is made up of a foraminated covering 22, preferably of woven wire or screen.

The flues 7, which draw the air through the condenser, are connected at each side of the machine with an air chamber 23, which is flattened out somewhat to fit against the side of the housing and extends down between the lateral supports 24, forming the framework, and the housing. This construction is shown in Fig. 2. The said chamber is preferably formed in two parts divided at 25, as shown in Fig. 3, to enclose the adjacent upper shaft 9. The lower portion of the air chamber is inclined laterally to fit about one side of the lower shaft 10; it extends below said shaft and is shaped to cover an arcuate opening, shown at 26, in the side of the housing immediately adjacent

the end of the lower cylinder. The inner sides of the chamber 23 are formed with openings therein to interfit with openings of the sides of the housing at the ends of the cylinders. The housing is therefore formed with outwardly extending rims 27, about the openings at the ends of the cylinders, and the air chambers have inwardly extending flanges 28 telescoping over said flanges 27 so as to form an approximately airtight fit between the parts.

The openings in the ends of the cylinder walls are made to correspond to the portion of the cylinder which is intended to form the screening area. It is desired that a certain restricted area upon each cylinder shall be cut off from the suction of the air so that when the cotton reaches this portion of the housing the cotton may be removed from the screen. In the upper cylinder 2 there is placed upon the shaft 9 an approximately triangular bracket 30. This bracket is fitted about the shaft 9 and held in position thereon by a set screw 31. It is contemplated that there shall be at least two of these brackets, one at each end of the cylinder. They are adapted to support a baffle, or shield, 32, which extends approximately radially outward from the shaft to the interior of the cylinder, and the ends of the two walls 32 are connected by an arcuate wall 33. This baffle, or shield, extends the full length of the cylinder and the area of the cylinder passing this cut off shield, or baffle, is thereby not exposed to the suction from the fan.

In the lower cylinder the brackets 34, which are mounted upon the shaft 10, are of different shape so as to accommodate a baffle, or shield 32', which is intended to shield a larger area of the lower cylinder than is done in the upper cylinder. The construction of a wall 33' is the same as in case of the upper shield, or baffle, except that it is of larger extent.

It will thus be noted that when the suction is exerted by the fan the draught of air will be caused to circulate inwardly through the opening 4 and against the screen area presented toward the opening, and in case of the upper cylinder the screen area will extend also over the upper portion of the screen as well. There will be, however, a restricted area protected by the wall 33 of the baffle, which will be cut off from the suction and thereby tend to release the cotton from the cylinder.

In the lower cylinder, the screening area is not as great but it will be noted that the suction is exerted upon the screen surface to a point rearwardly from the wall 32 of the upper cylinder so that if the cotton adheres to the screen of the upper cylinder after it has passed the wall 33 of the baffle, the suction passing through the screen sur-

face of the lower cylinder will tend to draw the cotton from the upper cylinder.

To assist in removing the cotton from the two cylinders, we provide a wiper roll 35. This roll is of the same length as the cylinders and is mounted upon a shaft 36 which is journaled at its ends in arms 37. These arms are fixed to shafts 38, journaled in the walls of the housing and having on their outer ends arms 39 extending forwardly and having at their other ends openings 40 for attachment to tension springs 41, secured at 42 to the housing and tending to draw the arms 39 downwardly and thus hold the roller 35 against the upper surface of the lower cylinder 3 at a point adjacent the upper baffle 32' thereof.

In the operation of this device, the suction caused by the fan will draw the lint through the opening 4 in the housing against the cylinders 2 and 3. The lint will be engaged upon the screen of the cylinders and the air with dust therein will be drawn through the openings in the ends of the housing adjacent the cylinders and carried off through the flues 6 and 7 to be discharged.

The cylinders are arranged for rotation in opposite directions, the upper one in a clockwise direction, and the lower one in a counter-clockwise direction. The cotton will thus be carried between the cylinders and that upon the upper cylinder will be engaged by the roll 35 and carried downwardly against the upper face of the cylinder 3. The layer of cotton upon the lower cylinder will therefore include the cotton received from the upper cylinder, and this double layer will be loosened from the lower cylinder and carried to the rear at the point where the suction is cut off from the screen by the baffle 32'. It will therefore be discharged in a uniform layer, or bat, on to the floor of the housing to the rear of the cylinders where it may be removed. It will be noted that the roll 35 is caused to rotate by its resilient contact with the lower cylinder 3; its upper surface will be moving in a direction opposite to that of the surface of the screen on the upper cylinder and will therefore tend to wipe the cotton from the cylinder in a most efficient manner.

Furthermore, the draft into the housing due to a draft inwardly above the wiper roll that will help carry the bat of lint on to the roll and thus materially assist in carrying the cotton away from the cylinders. Its pressure upon the lower screen will be sufficient to cause the cotton to be compressed and moved by the roll away from the cylinder so that it can be discharged.

It is contemplated that one condenser of this type may handle the cotton from a large battery of delinting machines; it will

handle the cotton from one, or any other number up to 16 or more. The cotton thus discharged to the cylinders 2 and 3 will be received upon a maximum screening surface. Only such portion of the screen area will be cut off from the suction as is necessary to cause the efficient removal of the cotton from the screen. There will be no discharge of dust or lint into the room in which the operators are working and all of the lint will be saved for use. The further advantage of this device will be obvious to those skilled in the art.

What we claim to be new and desire to protect by Letters Patent is:

- 15 1. In a cotton condenser, a housing having a cotton receiving opening at one side thereof, spaced parallel shafts fixed against rotation in said housing, foraminated cylinders rotatable in contact with each other on said shafts, brackets on said shafts within said cylinders, baffles on said brackets extending along said cylinders on their sides away from said opening, a wiper roll contacting with the lower of said cylinders adjacent said baffles spaced slightly from said upper cylinder and rotating in the same direction as one of said cylinders, suction means at the ends of said cylinders, said 25 30 baffles being positioned to extend on one cylinder in advance of the line of contact and in the other to the rear of said line, to

allow said suction to be exerted upon a portion of the surface of the second named cylinder adjacent an obscured surface of the other in the manner described, said wiper roll being held resiliently in contact with and receiving the cotton from said second named cylinder.

- 20 2. In a cotton condenser, a housing having a cotton receiving opening at one side thereof and an opposite outlet opening, upper and lower foraminated cylinders rotatable on shafts mounted in said housing, means to create a suction into said cylinders, brackets on said shafts within said cylinders, shields on said brackets to obscure limited areas on said cylinders from said suction, the shielded area on the upper cylinder overlapping the shielded area of the lower cylinder, a wiper roll rotatable in the same direction as said upper cylinder and spaced slightly therefrom and resiliently contacting with the outer side of said lower cylinder whereby suction from said cylinders will 25 30 35 40 45 50 55 60 pass between said upper cylinder and said wiper roll to assist in clearing said upper cylinder of cotton lint in the manner described.

In testimony whereof we hereunto affix our signatures this 6th day of May A. D. 1925.

FRANK W. PROVOST.
GEORGE B. HAYWOOD.
